Design U.S. Appl. No. 29/427,769, filed Jul. 23, 2012, Shin.

Primary Examiner — Raphael Barkai

(74) Attorney, Agent, or Firm — Knobbe Martens Olson & Bear LLP

(57) **CLAIM**

The ornamental design for eyeglass components, as shown and described.

DESCRIPTION

FIG. 1 is a front perspective view of eyeglass components showing my new design;

FIG. 2 is a front elevational view thereof;

FIG. 3 is a rear elevational view thereof;

FIG. 4 is a left side elevational view thereof, the right side elevational view being a minor image thereof;

FIG. 5 is a top plan view thereof; and,

FIG. 6 is a bottom plan view thereof.

The broken lines in the Figures show portions of the eyeglass which form no part of the claimed design.
